United States Patent Office.

JOHN LEONARD, OF BASIL, OHIO.

Letters Patent No. 78,979, dated June 16, 1868.

IMPROVEMENT IN PORTABLE FENCE.

The Schedule referred to in these Letters Patent and making part of the same.

TO ALL WHOM IT MAY CONCERN:

Be it known that I, JOHN LEONARD, of Basil, in the county of Fairfield, and State of Ohio, have invented a new and improved Portable Fence; and I do hereby declare that the following is a full, clear, and exact description thereof, which will enable others skilled in the art to make and use the same, reference being had to the accompanying drawings forming part of this specification.

Figure 1 is a side view of a portion of my improved portable fence.

Figure 2 is a vertical cross-section of the same, taken through the line x x , fig. 1.

Similar letters of reference indicate corresponding parts.

My invention has for its object to furnish an improved portable fence, strong, simple in construction, and easily put up, taken down, or moved from place to place; and it consists in the construction and combination of the various parts, as hereinafter more fully described.

A and B represent two adjacent panels of my improved fence, and which are formed by attaching the end of the horizontal bars a^1 and b^1 to vertical bars a^2 b^2 .

When the panels are long, they may be strengthened by attaching a central vertical bar, a^3 b^3 , to the centres of the horizontal bars a^1 b^1 , as shown in the drawings.

In erecting the fence, the lower ends of the vertical bars a^2 b^2 a^3 b^3 may rest upon the ground, or upon stone or wooden supports, and the panels are so placed that their adjacent ends may overlap each other sufficiently to bring the vertical bars, a^2 b^2 , opposite each other. C are inclined braces, the upper ends of which are slotted to receive the upper ends of the two adjacent vertical bars a^2 b^2 , which are then secured in place by wedges, D. The lower ends of the inclined braces C are also slotted, to receive the upper ends of the short posts or stakes E.

The posts or stakes E are notched upon their outer sides, and the lower ends of the inclined braces C are secured to them by the wedges F, as shown in fig. 2.

The lower parts of the panels A and B are supported against side pressure, and held together by the braces G, the lower ends of which are notched, to take hold of the horizontal bars of the said panels, and the upper ends of which are pinned or otherwise secured to the inclined braces C, as shown in fig. 2.

When the panels A and B are long, or for any cause need additional security, the shorter inclined braces, H, may be used, the upper ends of which are notched and slotted, to take hold of the central vertical bars, a^3 and b^3 , and the lower ends of which are slotted, and secured to short notched posts or stakes, I, by wedges, J, in the manner hereinbefore described with reference to the braces C and posts or stakes E.

K are longitudinal bars or slats, attached to the inclined braces C and H to protect hedges, &c., planted along the line of the fence from being injured or destroyed by stock.

If desired, the top of the fence or the inclined braces C may be protected from the weather by cap-boards, L, as shown in the drawings.

I claim as new, and desire to secure by Letters Patent—

1. Securing the panels A and B to each other, and in an erect position, by the inclined braces C and G, short notched posts or stakes E, and wedges F and D, substantially in the manner herein shown and described, and for the purpose set forth.

2. Strengthening the panels A and B in position by the inclined braces H, short notched post or stakes I, and wedges J, substantially as herein shown and described, and for the purpose set forth.

JOHN LEONARD.
